Inventor.

UNITED STATES PATENT OFFICE.

WILLIAM F. RAYMOND, OF SANDUSKY, OHIO.

PAD FOR HORSES' HOOFs.

SPECIFICATION forming part of Letters Patent No. 252,251, dated January 10, 1882.

Application filed October 3, 1881. (No model.)

To all whom it may concern:

Be it known that I, WILLIAM F. RAYMOND, of the city of Sandusky, in the county of Erie, in the State of Ohio, have invented a new and useful Barn and Road Pad for a Horse's Hoof, which is fully set forth in the following specification and accompanying drawings, in which—

Figure 1 is a plan view of my improved pad. Fig. 2 is a bottom plan of the horseshoe and pad. Fig. 3 is a plan view of the pad-fastening detached; and Fig. 4 is a top plan, showing the position of the same in relation to the shoe.

Corresponding parts in the several figures are denoted by like letters of reference.

A in the drawings refers to the pad, which may be of leather, rubber, or other suitable material, and which is of such a shape as to fit nicely within the inner rim of the shoe B.

C is a flat spring, embedded transversely in the pad A, or placed between the layers of material of which said pad is made.

D is a wire bail, the ends of which are firmly attached to the spring C, while the bail projects forward beyond the front end of the pad, thus forming a loop, E, capable of being ad-

justed upon a hook, F, at the front end of the horseshoe.

In operation, after adjusting loop E upon hook F, the pad is partly bent in order to enable the projecting ends G of the spring C to be introduced between the hoof and the sides of the shoe, thus retaining the pad in its proper position. The bail or loop, being adjusted upon hook F, prevents the pad from sliding backward.

This invention is very simple and inexpensive. It is easily adjusted or removed, and it forms an effective protection for horses' feet.

Having thus described my invention, I claim and desire to secure by Letters Patent of the United States—

The elastic pad A, having transverse flat spring C, from which a wire bail, D, projects forward to form a loop, E, said flat spring having projecting ends G, in combination with the shoe B, having hook F, substantially as set forth.

WILLIAM F. RAYMOND.
